SAFETY ASH TRAY

Byron T. Wall, Raymond, Alberta, Canada

Application November 15, 1934, Serial No. 753,193
In Canada November 17, 1933

10 Claims. (Cl. 131—51)

This invention relates to ash trays and more particularly to means for extinguishing lighted cigars and cigarettes.

Heretofore considerable damage has been caused by lighted cigars and cigarettes falling from the rests of ash trays and it is therefore an object of the invention to provide an ash tray embodying a rest for the cigar or cigarette in which means are incorporated, actuated by the heat of the lighted cigar or cigarette, for extinguishing the fire thereof, by a snuffing or smothering action.

It is also an object of the invention to provide a cigar or cigarette rest in which the lighted cigar or cigarette is firmly grasped and held against displacement therefrom until the cigar or cigarette has become extinguished.

Additional objects, advantages and features of invention will be apparent from the following description and accompanying drawing, wherein

Figure 1 is a fragmentary side elevation of an ash tray equipped with my invention.

Figure 2 is a fragmentary top plan view thereof.

Figure 3 is a sectional view on the line 3—3 of Fig. 2.

Figure 4 is a top plan view of a modification.

Figure 5 is an end elevation thereof.

Figure 6 is a cross section on the line 6—6 of Fig. 4.

Figure 7 is a top plan view of a further modification.

Figure 8 is an end view thereof.

Figure 9 is a cross section on the line 9—9 of Fig. 7.

In carrying out the invention I make use of any conventional ash tray generally indicated at 10 in Figures 1 to 3, upon the rim 11 of which there is mounted, in the present instance, a pair of rests 12 and 13. Any number of rests may be employed, and they may vary in size to accommodate either a cigar or cigarette. The present drawing shows the rest 12 for receiving a cigarette and the rest 13 for accommodating a cigar.

The rests 12 and 13 are identical in construction, and therefore a description of one will be applicable to both. The rest comprises a plate 14 having a slight curvature upwardly as viewed in end elevation, the curvature being such as to permit the laying of a cigar or cigarette longitudinally therewithin. The plate 14 is affixed to the rim 11 in any approved manner, as by soldering, brazing, or small rivets may be employed.

The rest is of a length to project well over the tray 10, and the plate 14 is cut away as at 15,

defining a medial tongue 16. The tongue 16 is bent downwardly from the plate, at a slight angle, and stops short of the base 17 of the tray, where it is given a right angular bend, defining a foot 18. The foot 18 affords a support for a cigar or cigarette snuffer 19.

The snuffer 19, in the present instance, is of substantially U-shaped formation, the bight portion 20 of which is positioned upon the foot 18, where it is secured by soldering, brazing or riveting. The snuffer thus constructed provides a pair of spaced leg members 21 disposed upon opposite sides of the tongue 16.

The snuffer 19 is formed of thin, flexible bimetal and the legs 21 extend a distance above 15 the tongue 16, and normally occupy a position so as to readily receive a cigar or cigarette therebetween. Obviously, when the lighted cigar or cigarette is laid upon one of the rests 12—13 with the burning end disposed over the tray 10, the 20 heat radiated from the cigar or cigarette will cause the legs 21 to swing or flex toward each other to such an extent that the burning portion of the cigar or cigarette will be extinguished by a snuffing action. It should also be noted that when 25 the legs 21 are moved toward each other, the cigar or cigarette will be firmly held upon the rest without liability of displacement therefrom, and will be so retained until the thermostatic action of the snuffer ceases to function, which 30 would only occur upon cessation of heat developed by the burning tobacco.

In Figures 4, 5, and 6 a modification of the device is shown, in which the tray 22 supports a rest 23 upon one edge of which a pair of bearings 24 are integrally formed. The rest 23 is preferably so shaped as to insure that the cigar or cigarette when laid therein will be disposed adjacent the bearings 24 so as to be in a position to be readily acted upon by a snuffer, as will be 35 described.

Journalled within the bearings 24 there is a small shaft 25, which has integrally formed upon one end thereof a hood-like member 26. The hood 26 is slightly curved, conforming to the 45 shape of a cigar or cigarette and cooperates with the rest 23 in extinguishing the cigar or cigarette. The opposite end of the shaft 25 has an enlargement 27 maintaining the shaft in position. A thermostatic spring 28 is provided, in the present 50 instance being shown in the form of a spiral, the inner end of which is secured to a pintle 29, the outer end being fixed to the hood 26. The pintle 29 is loosely journalled in a bearing or guide block 30 on the flange 31 of the tray. The 55

spring 28 normally has a position in a plane at a slight angle to the rest 23 so that the lighted end of the cigar or cigarette will engage the spring when laid in the rest. In operation, when 5 the spring is influenced by heat, the tendency will be for the spring to extend itself in a longitudinal direction, and since such action is restricted, due to anchorage of the shaft 25, the inner end of the spring will tend to move axially 10 away from the heat. This axial movement will be restricted to a limited degree by the pintle 29 and bearing 30, thereby imparting a rotary movement to the shaft 25, swinging the hood 26 into a position to engage and smother the fire 15 of the cigar or cigarette.

In Figures 7, 8, and 9 a modification of the hood is shown. In this form, the hood 32 is of a length substantially that of the rest 33 so that a greater portion of the cigar or cigarette will be 20 grasped during the smothering or stifling action. In this form the shaft 34 may be formed integrally with the hood and the bearings 35 so spaced as to receive the hood therebetween. The bearings 35 in addition to journaling the shaft, 25 also limit end thrust of the shaft under action of the thermostat.

It will of course be understood that as soon as combustion ceases, the parts return to normal position upon cooling of the thermostatic elements.

If found necessary, in the form disclosed in Figures 7, 8 and 9, the flange 36 of the tray may be provided with a suitable foot 37 to prevent tipping of the tray.

35 While I have shown and described certain preferred forms of the invention it should be understood that these are illustrative only and not restrictive, for it will be apparent that modifications may be made within the scope of the appended claims.

I claim:—

1. In a safety ash tray, a rest for cigars or cigarettes, a hood member, a heat responsive member arranged to be influenced from the combustion of a lighted cigar or cigarette to move the hood member into position with the cigar or cigarette to smother and stop combustion.

2. A safety ash tray, consisting of a rest for cigars or cigarettes, a movable member associated therewith and a heat responsive member so arranged that when the heat from a lighted cigar or cigarette nears the heat responsive member, it acts upon the movable member forcing it into position relative to said cigar or cigarette 55 to stifle and stop combustion.

3. In a safety ash tray, a rest, a thermostatic element, a hood or the like so associated therewith as to be acted upon when the heat from a burning cigar or cigarette nears the thermostatic 60 element to smother or extinguish the cigar or cigarette and so designed that upon completion of said action the parts will return to normal position.

4. A smoker's article consisting of an ash receptacle upon which there is a rest and a thermostatic device which is connected to a hood or like means and reacts from the heat of a lighted cigar or the like when the heat therefrom nears said thermostatic means to cause the hood to extinguish, stifle, suffocate or strangle combustion of said cigar or the like.

5. A rest for a lighted cigar or the like comprising a heat responsive element cooperative 10 with the rest for gripping, smothering and stifling combustion of the cigar.

6. In a safety ash tray, a rest for a lighted cigar or the like, said rest extending inwardly over the tray, a substantially U-shaped bi-metallic member supported within the tray, the legs of the U-shaped member being disposed upon opposite sides of the rest and terminating above the rest and adapted to embrace the cigar, whereby said leg members will be forced toward 20 each other under action of combustion of the cigar.

7. In a safety ash tray, a rest for a lighted cigar or the like, said rest extending inwardly over the tray, a bi-metallic member supported with- 25 in the tray and having flexible leg members disposed upon opposite sides of the rest and terminating above the rest and adapted to embrace the cigar, whereby said leg members will be flexed toward each other under action of heat 30 of the burning cigar.

8. In a safety ash tray, a rest for a lighted cigar or the like, parallel spaced ears formed on the rest, a shaft journalled in the ears, a snuffer carried by the shaft cooperative with the rest to 35 engage the lighted end of a cigar, and thermostatic means associated with the shaft and operative under action of heat generated by combustion of the cigar to rotate said shaft.

9. In a safety ash tray, a rest for a lighted ci- 40 gar or the like, parallel bearings on the rest, a shaft journalled in the bearings, a hood member carried by the shaft cooperative with the rest to engage the lighted end of a cigar, a spiral thermostatic member disposed to one side of the 45 rest and adjacent the position of a cigar when laid within the rest, the outer end of the spiral thermostatic member being secured to the shaft, and the inner end thereof having sliding anchor- age means with the tray.

10. In a safety ash tray, a rest for a lighted ci- 50 gar or the like, parallel bearings on the rest, a shaft journalled in the bearings, a hood mem- ber carried by the shaft cooperative with the rest to engage the lighted end of a cigar, a spiral 55 thermostatic member disposed to one side of the rest and adjacent the position of a cigar when laid within the rest, the outer end of the spiral thermostatic member being secured to the shaft, a guide bearing on the tray and a pintle to the 60 inner end of the spiral thermostatic member and slidably in said bearing.

BYRON T. WALL.
